BASEBALL AND METHOD OF MANUFACTURING SAME

Eli A. Robinson, Amsterdam, N. Y., assignor to
 Collette Manufacturing Company, Amsterdam,
 N. Y., a corporation of New York

Application July 25, 1935, Serial No. 33,007

5 Claims. (Cl. 273—60)

This invention relates to the method of manufacturing soft baseballs or playground balls and particularly to the process of treating the covering material of such balls both before and after the same are sewed about the center fillers.

An important object of my invention is to produce a soft baseball or playground ball in such a way that the cover or jacket of the ball may be sewed by a sewing machine about a center core of compressed filling material instead of being sewed by hand as is originally done in present day practice.

Other objects and advantages of my invention will become apparent or be specifically referred to in the following description thereof written in connection with the accompanying drawing, in which:

Figure 1 shows a grouped view of two pieces of material cut to form, when sewed together edge to edge, a ball cover.

Figure 2 illustrates an assembled view of the compressed ball filler or core and cover after the two pieces forming the cover are partially sewed together and the compressed core disposed therein.

Figure 3 illustrates diagrammatically the loose, wrinkled condition of the ball cover after it is completely sewed about the filler.

Figure 4 illustrates the condition of the cover after it has been shrunk to fit snugly about the filler.

Figure 5 illustrates a cross sectional view taken on line 5—5 of Figure 4 and looking in the direction of the arrows and showing the general appearance of the finished jacket and seams.

Figure 6 illustrates a ball similar to that shown in the other figures except that the cover is sewed together by what may be described as a flat seam or stitch, that is, one in which the pieces of cover material abut one another edge to edge.

Figure 7 is a fragmentary sectional view taken on the line 7—7 of Figure 6 and looking in the direction of the arrows.

Referring now to the drawing, Figure 1 illustrates two identically shaped blanks 11 cut from any suitable material, preferably a chrome tanned leather, and having a configuration such that when the two pieces are joined together at the points 12—12 and said pieces sewed together in two directions for a distance indicated by the numerals 12, 13, 14 they will form the partially sewed cover illustrated by the numeral 15 in Figure 2. For the want of a better name, I shall refer to the cover in this partially sewed state as forming a pocket. Before sewing the

pieces of the cover together, as above described, they are soaked in water and thoroughly wet so that the leather is soft and very stretchy.

After the cover is partially sewed, as above described, and while it is still wet, and preferably without removing the same from the sewing machine, or breaking the stitching thread, a more or less rigid and compressed center 16, made of felt, excelsior, rags or any other suitable material, is disposed therein, as shown in Figure 2. Thereafter the remaining unsewed edge portions of the cover are sewed together on a sewing machine.

It will be understood that the soft, wet leather may be stretched sufficiently to permit the edges thereof, notwithstanding the presence of the center 16, to be operated upon by a sewing machine and sewed together the remainder of the distance, just as the first sewing operation was performed on the edge portions 12 to 14 above described. Figure 3 illustrates the general appearance of the completely covered ball after the second or final sewing step has been performed. Attention is particularly called to the fact that the cover is, after the completion of this operation, noticeably wrinkled and baggy.

The covered balls are then bathed in live steam or otherwise heated, such as being immersed in boiling water, which almost instantly shrinks the cover over the core as shown in Figure 4. After the covers are thus shrunk to the cores, the balls are allowed to dry. It will be understood that when the covers of the balls are dried they become set and taut against the core and that the balls may then be used if desired.

I have found, however, that it is preferable to finish the outside surface of the leather cover and particularly the hard, dry rough portions of the edges of the seams by tumbling, for a time, a quantity of balls in a tumbling barrel. As a result of this tumbling operation, the rough portions of the edges of the seams are softened or rubbed smooth and the leather cover generally acquires a suede-like nap which gives to the finished balls a pleasing appearance to the eye and makes them pleasing to touch.

It will be seen, from Figure 5, that the seams are made in the covers by stitching through two thicknesses of the material so that the seams stand out slightly from the surface of the ball when the cover is shrunk to the core. This may be described as a welt seam. It will be understood, however, that other types of seams may be employed, such for example, as those shown in Figures 6 and 7, wherein the cover pieces are

sewed together by a machine making what may be described as a flat stitch and in which the pieces of cover material abut one another edge to edge.

5 While I have described what seems now to be the preferred embodiments of my invention, it is conceivable that various modifications in the configuration, composition and disposition of the component elements going to make up the same 10 may occur to those skilled in the art, and no limitation is intended by the phraseology of the foregoing description or illustration in the accompanying drawing.

What is claimed is:

15 1. The method of covering ball centers with a tight-fitting machine sewed cover made of suitably formed pieces of leather, comprising soaking the pieces of said leather cover in water until they are soft and stretchy, simultaneously stitching 20 and sewing on a sewing machine said leather pieces together about a ball center, steaming the ball thus made to shrink the cover to the center, drying the ball, and thereafter tumbling the same to finish the seams and outside surface of the 25 cover.

2. The method of covering ball centers with a tight-fitting machine sewed cover made of suitably formed pieces of chrome tanned leather, comprising soaking the pieces of cover leather in 30 water until they are soft and stretchy, sewing said cover pieces together about a ball center after said pieces are stretched sufficiently for the edges thereof to be stitched together on a sewing machine to form a welt seam, steaming the ball thus 35 made to shrink the cover to the center, drying the ball, and thereafter tumbling the same to finish the seams and outside surface of the cover.

3. The method of making baseballs having a

leather covered core comprising the steps of soaking in water a plurality of pieces of leather cut to a shape suitable for covering a ball, sewing the edges of said pieces together for a distance sufficient to form a pocket, disposing a core in said 5 pocket, stretching the cover about said core sufficiently to enable the unsewed edge portions thereof to be sewed together on a sewing machine, heating the cover thus sewed about the core to shrink the same to said core, and drying the cover 10 and core.

4. The method of making baseballs having a leather covered core comprising the steps of soaking in water a plurality of pieces of leather cut to a shape suitable for covering a ball, sewing the 15 edges of said pieces together for a distance sufficient to form a pocket, disposing a core in said pocket, stretching the cover about said core sufficiently to enable the unsewed edge portions thereof to be sewed together on a sewing machine, 20 immersing in boiling water the cover thus sewed about the core to shrink the same to said core, and drying the cover and core.

5. The method of covering ball centers with a tight-fitting machine sewed cover made of suitably formed pieces of leather, comprising soaking the pieces of said leather cover in water until they are soft and stretchy, simultaneously stitching and sewing on a sewing machine said leather pieces together half way around, then without 25 breaking the stitches or removing the cover from the machine the center is inserted and the cover is sewed the balance of the way around the ball center, heating the ball thus made to shrink the 30 cover to the center, drying the ball, and thereafter tumbling the same to finish the seams and the outside surface of the cover.

ELI A. ROBINSON.
